UNITED STATES PATENT OFFICE

2,157,446

WATER COOLER

Guido J. Wiggenhorn, South Pasadena, Calif.

Application November 10, 1936, Serial No. 110,101

5 Claims. (Cl. 62—91.5)

My invention relates to a water cooler and while of general application it is especially intended for use with drinking water dispensers used in offices where the demand on such dispensers is made for a period of, say, from seven to eight hours.

A common construction of such dispensers includes a cooling arrangement usually of porous clay type construction of a water container which by the action of evaporation of water seeping to the exterior of the container cools the water within but, as well known, in hot weather and especially when the humidity of the air is high and a heavy demand is made upon the water dispenser, the cooling effect is insufficient to maintain the water at the desired temperature.

It is an object of this invention to provide means using dry ice as the refrigerant to effectively cool the water in such drinking water dispensers for a period of seven to eight hours. It contemplates further the servicing with dry ice of such water dispensers every morning. Dry ice, while an excellent refrigerant in producing low temperatures, has the disadvantage that its specific heat is low and therefore a rather large quantity of dry ice is required to effect the cooling of the water for any considerable length of time.

In particular, the object of this invention is to use dry ice within the body of the water of the dispenser with means whereby the refrigerant action of the dry ice is retarded and while it cools the water sufficiently for the purpose intended it will within the limitations imposed by the cost of the service and the size of the cooling device effect the cooling of the water for the length of time desired.

It is another object of this invention to provide a double-walled chamber projecting horizontally inwardly into the body of the water of the dispenser, with means whereby the chamber formed by the double walls produces a slow circulation of the water therein, which acts as a thermal insulating body surrounding the space in which the dry ice is placed, thus retarding the evaporation of the dry ice and prolonging its cooling effect.

With the above and other objects in view, which will appear as the description proceeds, my invention consists in the construction and arrangement of parts hereinafter described and claimed.

I have illustrated in the accompanying drawing a water cooler embodying my invention, in which:

Fig. 1 is a vertical cross section of a water dispenser provided with my cooling device.

Fig. 2 is a sectional view on the line 2—2 of Fig. 1.

Referring to the drawing, 1 indicates the water container of the conventional construction provided with a faucet or spigot 2 near the bottom. A conventional jacket 3 may be provided which is spaced from the water container 1 and provided with ventilating openings 4 and 5 at the bottom and top, respectively. To produce a refrigerant effect by means of evaporation the sides of the water container 1 may be covered with fibrous sheets 6, such as blotting paper, permitting the slow seepage of water therethrough, 15 said water passing through minute perforations 7. The container 1 shown in the drawing may be made of porous clay, in which event the blotting paper 6 may be omitted.

The features thus far described form no part 20 of the present invention, which consists in the cooling device designated as a unity by the numeral 8.

The same consists of a dry ice chamber 9, which is shown as a rectangular box projecting 25 horizontally inwardly from an opening 10 in the wall of the container 1, which opening it will be noted is spaced a short distance from the bottom of the container so that the proper circulation of water cooled by contact with the holding device 30 may be effected yet the quantity be limited to the ordinary demands made upon the water dispenser.

The dry ice chamber consists of an exterior wall 11 and an interior wall 12 spaced from each other so as to provide a closed insulating chamber 13 by means of a flange 14 which extends at right angles from the interior wall 12 and which passes beyond the exterior wall 11 and which is cemented to the wall of container 1. A heavily 40 insulated door or closure 15 hinged at 16 to flange 14 permits the insertion or removal of an open-topped dry ice receptacle 17.

A minute perforation 18 is provided in the top of exterior wall 11 and another 19 at the bottom 45 thereof. The interior wall 12 is likewise provided with a minute perforation 20 so disposed that any water dropping therethrough by gravity will fall into the receptacle 17.

Operation

50

A piece of dry ice indicated at 21 is placed in the receptacle 17. It is advisable to provide thermal insulating means, such as cork strips or 55

the like, 22, upon which the dry ice rests so as to retard the evaporating thereof.

A thermal insulating sheet made of cork fibrous material or the like 23 is placed on top of the dry ice and the door 15 is securely closed. Water will fill the insulating chamber 13 by reason of the openings 18 and 19 which, it should be noted, are minute that the flow of water therethrough is extremely slow. The water in chamber 13 coming in contact with the interior wall 12, which is cooled by the proximity of the dry ice, will flow slowly, being heavier than water less cold, downwardly and out through perforation of the exterior wall 11.

The water will also drop through the minute perforation 20 into the dry ice chamber and onto the insulating sheet 23, which also functions as a distributing pad of the water, and coming in contact with the dry ice will be converted into water ice indicated at 24 forming a shell about the dry ice and enclosing the same, thereby retarding the evaporation thereof.

The constant evaporation of the dry ice, however, will not cause said shell to be impervious but will allow evaporation to take place although at a reduced rate and the carbon dioxide generated is permitted to escape through a minute opening 25 in the door 15.

The cold in the dry ice chamber may be such that it will congeal the water dripping through perforations 20 on to the sheet 23 and seal the perforation until such time when the temperature will melt the water, permitting further ingress of the same to the chamber. If an excess of water should enter the dry ice chamber or after the dry ice is all evaporated, water may accumulate in said chamber, no harm will be done; it will merely flow through perforation 25 in the closure 15 into the drip pan 26, which also serves to receive any excess water flowing on the outside of container 1.

In this manner, by providing a cooling unit which is surrounded by water except at one side, the entire cooling effect of the dry ice is utilized and retarded in a manner as described so that while cooling the water the rate will be such that under ordinary calculated conditions of the size of the cooling units and the water container as well as the weather, a certain quantity of dry ice will keep the water cool for the number of hours for which it is designed.

Various changes may be made in the details of the construction without departing from the spirit or scope of the invention as defined by the appended claims.

I claim:

1. A water cooler comprising a water container, a dry ice chamber extending horizontally from the side wall of the water container into the interior and spaced from the bottom thereof, said dry ice chamber being formed with exterior and

interior walls forming a closed insulating chamber therebetween, said dry ice chamber having an open end flush with the side wall of the water container, a removable cover therefor, a removable open topped dry ice receptacle within the dry ice chamber, a support of thermal insulated material for the dry ice in the receptacle, a loose thermal insulating sheet to rest on the dry ice in the receptacle, the exterior wall of the dry ice chamber being provided with minute perforations to permit slow circulation of water through the insulation chamber, the interior wall of the dry ice chamber being provided with a perforation permitting water to drop onto the fibrous sheet.

2. In a water cooler comprising a water container, a dry ice chamber extending from the side wall of the container into the interior thereof, said dry ice chamber being formed with exterior and interior walls forming a closed insulating chamber there between, said dry ice chamber having an open end connected to the side wall of the water container, a removable lid therefor, an open topped dry ice receptacle within the dry ice chamber, a thermal insulating sheet to cover the top of the receptacle, means to permit a slow circulation of water through the insulating chamber and means to supply a small quantity of water from the insulating chamber onto the fibrous sheet.

3. In a water cooler comprising a water container, a dry ice chamber extending into the interior thereof and having an open end secured to the side wall of the water container, said dry ice chamber being formed with exterior and interior walls forming a closed insulating chamber therebetween, a removable closure for the open end of the dry ice chamber, a removable dry ice receptacle within the dry ice chamber, means permitting the slow circulation of water through the insulating chamber and means to supply a small quantity of water to the dry ice receptacle.

4. A water cooler comprising a water container, a dry ice chamber extending into the interior thereof, said dry ice chamber being formed with exterior and interior walls forming a closed insulating chamber therebetween, a removable closure for the dry ice chamber, a dry ice receptacle within the dry ice chamber, means permitting slow circulation of water in the insulating chamber and means supplying a small quantity of water to the dry ice receptacle.

5. In a water cooler comprising a water container, a dry ice chamber extending from a side wall of the container into the interior thereof, a removable lid for closing the dry ice chamber, an open topped dry ice receptacle within the dry ice chamber, the chamber above the receptacle being provided with a small perforation to supply a quantity of water from the water container to the dry ice receptacle.

GUIDO J. WIGGENHORN.
